United States Patent Office.

WILLIAM H. JOHNSON, OF PHILADELPHIA, PENNSYLVANIA.

Letters Patent No. 95,908, dated October 19, 1869; antedated October 5, 1869.

IMPROVEMENT IN WASH-PAVE KEY-HANDLE.

The Schedule referred to in these Letters Patent and making part of the same.

To all whom it may concern:

Be it known that I, WILLIAM H. JOHNSON, of the city and county of Philadelphia, and State of Pennsylvania, have invented a new and useful Improvement in Wash-Pave Key-Handles; and I do hereby declare that the following is a full and exact description thereof, reference being had to the accompanying drawings, and to the letters of reference marked thereon.

It is usual, in the use of the hose, to lay it on the top or handle of the key, the latter being in connection with the hydrant, for the purpose of stretching it to take out the kinks; and the handle being straight, the hose is liable to slip off.

To obviate this difficulty, I construct the handle of irregular form, so as to have one or more depressions, into one of which the hose is laid and kept intact, as will be understood by the following description.

In the accompanying drawings, which make a part of this specification—

Figure 1 is a side elevation of the key, with the improved handle.

Figure 2 is a top view of the same.

Like letters in both figures indicate the same parts.

A is the shank of the key, which has a socket, a, constructed in the usual manner.

B is the top or handle, which is bent to form depressions b b, into one of which the hose is laid, to stretch it, and whereby it is held securely, to prevent its slipping off.

I do not confine myself to constructing the handle B merely with curved depressions b b, as represented, as the object may be accomplished by giving variety to the curved formation of the top, or by angular depressions; as, for instance, a single curved depression will answer as well; and, also, one or more angular depressions will accomplish the same thing, the angular depressions having a V-shape, or other convenient form; or, the handle may be made straight, as usual, and turned up at the ends, or have upward-projecting shoulders, to prevent the hose slipping off.

What I claim as new, and desire to secure by Letters Patent, is—

The construction of a wash-pave key, with the handle of any irregular shape, whereby the hose is kept in position, substantially as described.

In testimony that the above is my invention, I have hereunto set my hand and affixed my seal, this 22d day of March, 1869.

WM. H. JOHNSON. [L. S.]
